ELECTROSTATIC MICROPHONE

Rudolf Görike, 15 Gregor Mendelstrasse, Vienna, Austria
Filed July 30, 1959, Ser. No. 830,558
Claims priority, application Austria Aug. 7, 1958
5 Claims. (Cl. 179—111)

This invention relates to electrostatic microphones having a stressed diaphragm with multiple support. In a known construction the support is pointwise and the support points are formed by embossing, electrolysis, milling (in the case of metal) or by casting (in the case of varnishes etc.) in the conducting or non-conducting material of the diaphragm or of the counterelectrode. This construction has the disadvantage that the manufacture of the multiple-supported diaphragm or counterelectrode with numerous support points is very complicated and expensive.

It's also known to divide the vibrating area of the diaphragm into several, separate zones and to provide a continuous support for the resulting surface portions of different configuration. Such supports were formed, e.g., by adhesively connected thin strips of paper. This resulted in a substantial decrease in the sensitivity of the microphone.

In another known construction the countersurface (counterelectrode) is provided with fine, raised, preferably linear ribs, which may consist of textile or silk fibers.

The invention provides a solution which is simple in manufacture and does not adversely affect the sensitivity and is characterized in that at least one plastic thread is wound as a support on the electrode so that the thread forms single, preferably parallel lines of support for the diaphragm.

According to another feature of the invention the portions of the plastic thread applied to the electrode are evenly spaced. The counterelectrode may be formed with evenly spaced notches at opposite edges and a thread lying in these notches may be wound on the counterelectrode.

Nylon or "Perlon" in a thickness of 20—40 microns is particularly suitable as a thread material.

By the measure adopted according to the invention the industrial manufacture of such microphones is substantially simplified because the thread can be continuously withdrawn from a supply bobbin and it is even possible to perform the entire winding operation with a very simple (bobbin) winder, in which several electrodes can be gripped one beside the other. In the case of the last-mentioned one of the known constructions it is either necessary to adhesively connect individual lengths of thread in a laborious operation or, where a continuous thread is used, each turn of the thread must be individually adhesively connected.

Two particularly suitable embodiments of the invention will be discussed by way of example with reference to the accompanying drawing, in which

FIG. 1 is a top plan view showing a diaphragm according to the invention and

FIG. 2 is an enlarged sectional view thereof.

FIG. 3 shows another possibility of arranging the threads.

A thread 1 is wound around the counterelectrode so that the notches 2 milled into the edge of the counter-

2

electrode provide for an equal spacing of the several portions of the thread. The diaphragm, consisting of insulating material, particularly of a thermoplastic, and vapor-coated with conducting material on one side, is adhesively connected to the thus wound counterelectrode the necessary stress is suitably applied to the diaphragm by giving the counterelectrode a small camber. FIG. 2 is a highly enlarged sectional view of the microphone according to the invention. 3 is the diaphragm, 1 the thread 20—40 microns thick, 4 the counterelectrode and 5 are the air passages.

Using the same reference characters, FIG. 3 shows a counterelectrode which has notches 2 on the parallel longitudinal edges. The thread 1 extends in a winding course over the counterelectrode and through the notches, i.e., it extends on the upper side of the electrode parallel thereto. The underside of the electrode has only short portions of thread at the edges.

I claim:

- 20 1. In an electrostatic microphone; the combination of a stressed diaphragm, an electrode having opposite edges formed with equally spaced notches therein, and at least one continuous plastic thread wound with a plurality of turns on said electrode and retained by said notches, sections of said turns extending across at least the surface of said electrode facing toward said diaphragm and forming single lines of support between said electrode and said diaphragm.
- 25 2. In an electrostatic microphone; the combination of an electrode having opposite edges formed with equally spaced notches therein, at least one continuous plastic thread wound with a plurality of turns on said electrode and passing through said notches with at least one section of each turn of said thread extending across one surface 35 of the electrode between said opposite edges of the latter, and a stressed diaphragm extending over said one surface of the electrode with said sections of the plastic thread forming spaced lines of support between said electrode and diaphragm.
- 30 3. In an electrostatic microphone; the combination as in claim 2, wherein said plastic thread wound on the electrode has sections thereof extending across the other surface of the electrode between said opposite edges and alternating with said sections of the thread extending 45 across said one surface.
- 35 4. In an electrostatic microphone; the combination as in claim 2, wherein said plastic thread wound on the electrode has sections thereof extending along the other surface of the electrode between successive notches in the same edge of the electrode and alternating with said sections of the thread extending across said one surface.
- 40 5. In an electrostatic microphone; the combination as in claim 2, wherein said sections of the thread are parallel to each other and spaced apart by equal distances.
